WILLIAM GEORGE WIESENER, OF SYDNEY, NEW SOUTH WALES, AUSTRALIA.

VALVE OPERATING AND LOCKING DEVICE.

1,384,369.

Specification of Letters Patent.

Patented July 12, 1921.

Application filed June 23, 1919. Serial No. 306,146.

To all whom it may concern:

Be it known that I, WILLIAM GEORGE WIESENER, a subject of the King of Great Britain and Ireland, and residing at "Dallas," Livingstone Street, Sydney, New South Wales, Commonwealth of Australia, have invented a certain new and useful Valve Operating and Locking Device, of which the following is a specification.

10 This invention relates to devices for preventing the unauthorized use of automobiles, internal combustion engines and the like.

More particularly the invention relates to a throttle or cock incorporated in the fuel 15 or induction pipe of an internal combustion engine whereby the supply of fuel thereto can be readily cut off and locked by means of a key and so render the engine unstartable except at the will of the owner or authorized 20 user.

One object of the present invention is to fit the locking attachment in such a way that should any attempt be made to force the lock it will damage a vital part of the engine 25 and render it useless.

Another object is to arrange the device in a single self-contained casing.

In my invention I mount within the casing 30 of the throttle valve or cock a lock of the "Yale" or any similar pattern, in such manner that the rotating bolt of the lock engages directly with the plug of the throttle valve or cock. I prefer to mount the throttle or cock in such position that any attempt to force 35 the locked device would damage a vital part such as the carburetor or induction pipe and still further prevent the engine being run. Such an arrangement provides a cheap and safe device attachable to any engine.

40 This invention is applied to the engine fuel in gas form, consists essentially of an air leak-proof throttle or cock in the fuel pipe leading from the carburetor to the engine, or incorporated in the carburetor itself, such 45 throttle or cock being wholly inclosed in a metal casing and so arranged as to be controlled externally solely by means of a key turning in a lock of "Yale" or similar pattern which is also securely housed in, and 50 protected by the said throttle casing. This casing is preferably embodied in a vital member such as the gas fuel pipe or the carburetor, the destruction of which would ensue upon any attempt to tamper with the 55 locked device. Normally, the throttle is open, allowing the gas fuel to pass freely

and feed the engine when running. The revolving bolt of "Yale" lock engages in and rotates the throttle, so that by turning and removing the key, the throttle can be closed 60 and locked, and the engine rendered unstartable.

The key is only removable when the throttle is closed, in which position it is locked by such removal, the said key forming the sole means whereby the throttle can be unlocked and engine restarted. The throttle is maintained in open position by a spring 65 designed to snap into a notch on the throttle head, the operating key remaining fixed in the lock.

70 By this arrangement the key cannot be lost or mislaid, and is always on hand when it is desired to lock up the fuel supply and render the engine unstartable. But in order 75 that my invention may be more clearly understood, reference will be made to the drawings which accompany and form part of this specification.

80 In the drawings,

Figure 1 is a vertical section of the device, as applied to the gas fuel pipe with the throttle closed and the key ready for withdrawal.

Fig. 2 is a front elevation with the throttle open and the key fast in the lock.

85 Fig. 3 is a plan of the throttle head, showing the slot in which the "Yale" revolving bolt engages and the "open" and "closed" notches with which the spring stop registers.

In Fig. 1, 10 is a cylindrical throttle revolving in the throttle casing 3-3, and provided with an air-tight joint 4, working in a suitable seat turned in the casing. The induction pipe 5-5 is recessed and soldered into each end of the casing 3-3, and the 90 throttle 10 carries an orifice 2, of the same bore as the induction pipe, which can be turned vertically to form a continuous passage, or laterally to close the pipe and shut off the gas supply. 6 is a circular metal disk 95 in which is securely mounted a "Yale" lock 7 in such position that the revolving bolt 8 carrying the key 9 is central with the throttle 10. The disk 6 is recessed into the end of the casing 3 and permanently secured 100 by pins 17-17 thus sealing the casing 3-3. Bolt 8 of the lock has a projecting tongue 12 engaging in a slot 15 in the head of the throttle so that the two are coupled and turn in unison. To the inner face of the 110 disk 6 is attached a U shaped spring 13, pressing the throttle 10 home in its air-

tight seating 4, and carrying at its point of contact a V shaped projection 14 which snaps into and engages notches 16 on the face of the throttle thus registering the true vertical 5 and horizontal positions of the orifice 2. In Fig. 1 the throttle is shown closed and when the key 9 is removed the "Yale" wards enter bolt 8 and lock it and consequently the throttle 10 and no gas can pass through the 10 induction pipe 5 until the key 9 is replaced and the bolt 8 is once more revolved carrying with it throttle 10 to the open position. Fig. 2 shows key 9 turned horizontally in which position it cannot be withdrawn but 15 remains fast in the device. The orifice 2 is now vertical and goes to form part of the induction pipe 5—5.

Fig. 3 is a plan of the head of the throttle 10 showing slot 15 in which the tongue 12 20 of the "Yale" bolt 8 engages and notches 16—16 registering the "open" and "closed" position of the throttle 10 through the snap action of the spring 13.

Having now described my invention, what

I claim as new and desire to secure by Letters Patent is:—

1. A locking device for controlling the operation of an internal combustion engine comprising in combination a fuel supply pipe, a sealed casing inserted in the piping 30 and having a conoidal seating, a cylindrical rotary valve in the casing with a conoidal portion at one end that engages the seating of the casing and means which both presses the valve upon its seating and indicates its 35 position when in the open and closed positions.

2. A locking device as claimed in claim 1 wherein the means comprises a spring secured to the casing and bearing directly 40 upon the valve to secure a fuel tight joint, the said valve having notches that engage the spring in order to indicate the positioning of the valve.

In testimony whereof I have signed my 45 name to this specification.

WILLIAM GEORGE WIESENER.
